ABRASIVE AND POLISHING DEVICE

Henry E. Tolman, Detroit, Mich.

Application July 11, 1932, Serial No. 621,883

1 Claim. (Cl. 51—209)

This invention relates to an improved abrasive and polishing device and to the method of making the same.

The main objects of the invention are to provide a device of this character which has the extremities of a multiplicity of strand-like abrading elements, such as strands of steel or other metal wool, exposed at its working surface; to provide an abrasive or polishing head which has a main body portion composed of strands of metal wool mounted on end and extending substantially normal to the working surface thereof so as to continuously maintain sharp cutting extremities of the strands at the working surface as the latter wears; to provide a device of this kind in which the strands are held in a compact mass under lateral compression and thereby prevented from bending in such a manner as to remove the extremities of the strands from the working surface; and to provide an abrasive head which is flexible and susceptible of bending into conformity with curved surfaces during its application thereto.

Other objects of the invention are to provide a method for mounting a multiplicity of strands of metal wool or other strand-like abrading members on end upon a support in a manner such that the strands mutually support each other in substantially parallel relationship and present a multiplicity of free extremities for abrading purposes; to provide a method of this character by which the strands are mounted on end upon a pad comprising flexible material and rigidly secured to the latter; to provide a method of this kind in which the ends of the strands on one side of the compact mass of strands are integrally bonded by vulcanization to a rubber pad; and to provide for the distribution of finely comminuted abrasive material throughout the entire mass of strands of a device of this character.

An illustrative embodiment of the invention is shown in the accompanying drawing, in which:

Fig. 1 is a side elevational view of a bundle of metal strands of the character embodied in metal wool and from which my improved abrasive head is formed, and illustrating the first operation to which the stranded material is subjected.

Fig. 2 is a side elevational view, partly in section, showing apparatus for compressing the metal strands and illustrating the manner in which they are arranged, as well as the compressing operation.

Fig. 3 is a plan view of the apparatus shown in Fig. 2 illustrating the compressing operation.

Fig. 4 is a vertical sectional view illustrating the step of removing a body of strands from the temporary contractible band and clamping ring shown in Figs. 2 and 3.

Fig. 5 is a view similar to Fig. 4, illustrating the removal of the body of compressed strands from the contracting band and clamping ring and illustrating the manner in which finely comminuted abrasive material may be distributed throughout the mass of the strands.

Fig. 6 is a view similar to Figs. 4 and 5 showing the final step in the removal of the compressed mass of metal strands and illustrating the manner in which the metal strands are bound together and maintained under lateral compression.

Fig. 7 is a side elevational view, partly in section, of an abrasive or polishing device embodying my invention which is adapted for attachment to a spindle or other drive member.

Fig. 8 is a side elevational view, partly in section, of an abrasive or polishing device embodying a further development of the invention and which is adapted to be manually manipulated.

My improved abrasive and polishing device may be conveniently and economically manufactured in the manner illustrated in the drawing with the aid of the apparatus shown therein. In the form shown the apparatus includes a bed or support 10 having a substantially flat upper face 11 on which is disposed a split, contractible collar 12 having overlapping extremities. Substantially completely surrounding the collar 12 are a pair of flexible bands 13, preferably comprising spring steel, both of which are rigidly fixed at one end 90 to a shoe 14 which is either pivotally or rigidly mounted upon the support 10. The other end portions of the bands 13 are coiled upon and fixed to a spindle 15 which is rotatably mounted in a substantially vertical upright position upon the support 10. The spindle 15 is provided on its upper end with a wheel 16 which may be turned by hand, or by power driven mechanism, so as to wind the bands 13 upon the spindle and thereby contract the split collar 12. The shoe 100 14 has an arcuate side face 17 against which the collar 12 is drawn during contraction of the latter.

The stock from which my improved polishing or abrasive device is constructed may either wholly or partly consist of metal strands 18 of the character employed in metal wool. Strands of this type are obtainable in loosely bound bundles of considerable length which may be conveniently cut up into sections 19 of uniform 110

lengths, as illustrated in Fig. 1. The strands may consist of metals, such as steel, bronze, aluminum, or other suitable metals.

The sections 19 are placed on end within the 5 contractible collar 12 while the latter is in an expanded state. Strands of different kinds of metal may be mixed together and placed within the contractible collar 12, if desired. In some instances, it may be found advantageous to in- 10 termingle with the metal strands, non-metallic strands comprising either hair-like vegetable or animal matter. When the interior of the expanded collar 12 is completely filled with sections of strands, the wheel 16 is turned so as to wind the 15 bands 13 thereon. In this manner the collar 12 is contracted and the strands 18 are tightly compressed laterally into a compact mass. A split clamping ring 20 is then disposed around the collar 12 and securely clamped thereon by 20 tightening a screw 21 so as to temporarily hold the mass of strands in a compressed state. The wheel 16 which may, if desired, be held against clockwise rotation, as viewed in Fig. 2, by a ratchet or other mechanism (not shown) is then 25 released and turned in a clockwise direction so as to loosen the bands 13.

The compressed mass of strands, together with the surrounding collar 12 and clamping ring 20, is removed from the support 10 and placed upon a 30 support 22 having a cylindrical passage 23 thereon substantially equal in diameter to the diameter of the compressed mass of strands 18. The outer periphery of the mass of strands 18 is brought into registration with the walls of the 35 passage 23 and a plunger 24 is inserted into the upper end of the collar 12 for the purpose of displacing the compressed mass of strands from the collar and inserting it into the passage 23. The displacement of the compressed mass of 40 strands from the collar 12 may be interrupted after the plunger 24 has been partially inserted into the collar 12 and the plunger may be withdrawn at this stage so as to permit a mixture of finely comminuted abrasive material 25 and 45 a suitable vehicle which may include cement, to be introduced into the upper end of the collar 12. The abrasive material is then distributed between the strands by pressure when the plunger 24 is reinserted into the collar 12 and extended 50 therethrough for the purpose of displacing the compressed mass of strands. If it is not desired to have a finely comminuted abrasive material distributed throughout the mass of strands, the plunger may be inserted completely into the collar 55 12 during a continuous operation while omitting the introduction of the abrasive material.

As soon as the end portions of the strands are projected far enough beyond the lower side of the support 22 they are firmly bound together by tape 26, or other suitable material 60 which retains the strands 18 in a lateral compressed state after the compressed mass thereof is removed from the passage 23 of the support 22 by further downward movement of the plunger 24.

After the strands are bound together by tape and are removed from the passage of the support 22 the bound end portions thereof are fixed to a suitable support 27 which may comprise rigid 65 or flexible material. In the form shown the pad

27 consists of rubber and it is integrally bonded by vulcanization to the extremities of the bound end portions of the strands 18. The rubber of the pad 27 may be extended over the peripheral portion of the pressed layer of strands to any desired extent and may, if desired, be formed so as to envelope the tape 26. If steel or other ferrous metal strands are employed, the extremities of the bound end portions of the strands are preferably plated with bronze or other metal to which rubber readily bonds during vulcanization. The rubber pad 27 may be moulded on and simultaneously vulcanized to the bound end portions of the strands. A threaded attaching member 28 is provided on the outer side of the pad 27 for the purpose of detachably connecting the device with either power or hand driven mechanism by which it may be rotated, reciprocated, or otherwise moved over a surface of a piece of work.

The abrasive or polishing device shown in Fig. 8 may be constructed in the precise manner illustrated and described above by employing sections of strands of shorter length than those shown in Fig. 1. The layer of rubber 29 in this form of polishing or abrasive tool is substantially thin and is provided with a band 30 which is adapted to fit over the back of a hand so that the device may be conveniently manually manipulated.

In both forms of the invention the working surface of the device is made up of a multiplicity of the extremities of strands which have substantially high cutting power. This working face may be machined to a desired concaved or convexed curvature. During operation of a device of this character the flexible pad or support to which the strands are fixed bends freely during movement of the device over a curved surface of a piece of work. The lateral compression under which the strands are held maintains them in substantial parallel relationship and they are thereby mutually supported by each other against bending in such a manner as to remove the extremities of the strands from the working 110 surface of the device.

Although but several specific embodiments of the invention are herein shown and described, it will be understood that various changes in the size, shape, and arrangement of parts may be 115 made without departing from the spirit of my invention, and it is not my intention to limit its scope other than by the terms of the appended claims.

What I claim is:

An abrasive device including a backing comprising a flexible rubber composition, an abrading member having substantially greater transverse dimensions than thickness and comprising a multiplicity of metal strands arranged in 135 side to side, substantially parallel, and metal to metal contacting relationship with corresponding extremities on opposite sides of said member respectively, the end portions of said strands on only one side of said member being bonded by 140 vulcanization to and engaged by said rubber backing and the opposite extremities of said strands constituting the working surface of said device.

HENRY E. TOLMAN.
